UNITED STATES PATENT OFFICE.

JULIUS WILHELM VON PITTLER, OF GOHLIS, LEIPSIC, SAXONY, GERMANY.

EMBROIDERING ATTACHMENT FOR SEWING-MACHINES.

SPECIFICATION forming part of Letters Patent No. 378,383, dated February 21, 1888.

Application filed June 19, 1886. Serial No. 205,690. (No model.) Patented in Germany December 30, 1885, No. 39,491; in France January 22, 1886, No. 173,692; in Belgium February 15, 1886, No. 71,980; in England May 31, 1886, No. 7,254; in Sweden June 1, 1886, No. 929; in Spain June 4, 1886, No. 9,581; in Norway June 8, 1886, No. 123; in Italy June 22, 1886, No. 20,554; in Denmark October 14, 1886, No. 788, and in Austria-Hungary February 5, 1887, No. 38,694 and No. 69,653.

To all whom it may concern:

Be it known that I, JULIUS WILHELM VON PITTLER, a subject of the Emperor of Germany, residing at Gohlis, Leipsic, in the Kingdom of Saxony and Empire of Germany, have invented an Embroidering Attachment for Sewing-Machines, of which the following is a specification.

This invention is embodied in the following patents: German patent, No. 39,491, dated December 30, 1885; French patent, No. 173,692, applied for January 22, 1886, issued May 3, 1886; Austro-Hungarian patents, Nos. 38,694 and 69,653, applied for February 15, 1886, issued February 5, 1887; Belgian patent, No. 71,980, applied for February 15, 1886, issued February 27, 1886; English patent, No. 7,254, dated May 31, 1886; Swedish patent, No. 929, applied for June 1, 1886, issued September 2, 1887; Spanish patent, No. 9,581, applied for June 4, 1886, issued September 27, 1886; Danish patent, No. 788, applied for June 4, 1886, issued October 14, 1886; Norwegian patent, No. 123, applied for June 8, 1886, issued October 6, 1886; Italian patent, No. 20,554, applied for June 22, 1886, issued October 13, 1886.

My improvement consists in certain features of construction by which a pantograph is adapted to an embroidering attachment for ordinary sewing-machines, as hereinafter described, and pointed out in the claims. In another application, Serial No. 190,500, filed February 1, 1886, I have shown, described, and claimed another form of such embroidering attachment for ordinary sewing-machines.

In order that my invention may be fully understood, I will proceed to describe it with reference to the accompanying drawings, in which—

Figure 1 is a plan view of my improved embroidering attachment. Fig. 2 is a plan view of a modification thereof. Fig. 3 is a plan view of another modification.

A is the cloth-frame supported in clamping-jaws. To these clamping-jaws are pivoted, at their inner ends, two links, *a a'*, connected by pivots at their outer ends to a bar, *b*, having a slot, *c*.

e e' and *f f'* are the arms of inner and outer toggle-levers, which are connected at their

outer ends, by a pivot, *d*, to the slot *c* of the 50 bar *b*.

i is a guide rail or plate, to which the middle pivot of the inner toggle-lever is secured, adapted to be secured to the cloth-plate of a sewing-machine, having a slot, *h*, in which is 55 pivoted the middle pivot, *g*, of the outer toggle-lever. The slotted bar *b* and slotted guide rail or plate *i* permit the free and unimpeded motion of the cloth-frame, thus keeping up a constantly-uniform relation of the parts *a a'*, 50 *e e'*, and *f f'* to each other. In this arrangement the pantograph B forms a part.

The arrangement of the attachment in Fig. 2 is substantially the same as that in Fig. 1, excepting that in this case the bar *b* and inner 65 toggle are dispensed with, thus limiting the extent to which this arrangement can be used, as the relations of the parts to each other do not remain equal whenever the outstroke of the point *k* of the pantograph B is too great. 70

The arrangement of the attachment in Fig. 3 shows a lever mechanism arranged in the form of two perpendicularly - counteracting parallelograms, C and D, in which the leg *l* of the parallelogram C is stationary, while the 75 clamping-jaws are fastened to the leg *o* of parallelogram D. Pantograph B is fastened above the parallelograms and pushes the clamping-jaws by means of the leg *o* of the parallelogram D, according as the work requires. 80

The frame A consists of two frames or rings—the inner ring, *r*, and the intermediate ring, *q*. The inner ring is quite smooth and simple. The intermediate ring is cut or cleft and formed with a rough inside, and can be drawn together 85 by means of a screw, S.

p p are the spring clamping-jaws which engage the frame A, and are connected to the lever mechanism or to the pantograph.

The fabric to be embroidered is first laid on 90 the inner ring and then the intermediate ring is pressed over it. Owing to the rough inner side of the latter, it carries the fabric with it and draws it tight. The ring *q* is then drawn together by the screw S, and the rings thus 95 connected are jammed together with the fabric into the clamping-jaws, which are connected to the lever mechanism or pantograph.

I claim—

1. An embroidering attachment for sewing-machines, comprising a cloth-frame provided with an inner frame or ring and an intermediate frame or ring, and a pantograph lever mechanism provided with clamping-jaws, substantially as described.
2. An embroidering attachment for sewing-machines, comprising a cloth-frame provided with an inner ring and an intermediate ring, a pantograph lever mechanism provided with clamping-jaws, and a guide rail or plate adapted to be secured to the cloth-plate of a sewing-machine, substantially as described.
3. An embroidering attachment comprising a cloth-frame provided with an inner plain ring, and an intermediate ring formed with a rough inner surface and having an adjusting-

screw, and a pantograph having spring clamping-jaws which engage the said cloth-frame, 20 substantially as described.

4. The combination of the cloth-frame A, having an inner ring, *r*, and intermediate ring, *g*, a guide-rail, *i*, and pantograph lever mechanism having clamping jaws which engage the 25 said cloth-frame, substantially as described.

5. The combination of the cloth-frame A, links *a a'*, toggle-levers *e e' f f'*, having pivot *d*, bar *b*, having slot *e*, guide-rail *i*, having slot *h*, and the arms B of the pantograph, substantially as described.

JULIUS WILHELM VON PITTLER.
